UNITED STATES PATENT OFFICE.

FRANK ROSOSZUK, OF ALBANY, NEW YORK.

DESIGN FOR A SADIRON-HANDLE.

56,032.

Specification for Design.

Patented Aug. 10, 1920.

Application filed February 13, 1920. Serial No. 358,397. Term of patent 7 years.

To all whom it may concern:

Be it known that I, FRANK Rososzuk, a citizen of Poland, residing at Albany, in the county of Albany and State of New York, have invented a new, original, and ornamental Design for a Sadiron-Handle, of which the following is a specification, reference being had to the accompanying drawing, forming part thereof.

The figure is a view in perspective of a sadiron handle, showing my new design.

I claim:

The ornamental design for a sadiron handle, as shown.

FRANK ROSOSZUK.
